UNITED STATES PATENT OFFICE

158,853

OIL CHANGER

John D. Gray, Evanston, Ill.

Application April 1, 1949, Serial No. 1,760

Term of patent 3½ years

(Cl. D14—3)

To all whom it may concern:

Be it known that I, John D. Gray, a citizen of the United States, residing at Evanston, in the county of Cook and State of Illinois, have invented a new, original, and ornamental Design for Oil Changers, of which the following is a specification, reference being had to the accompanying drawing, forming part thereof.

Fig. 1 is a front perspective view of an oil changer showing my new design;

Fig. 2 is a rear perspective view of the same; and

Fig. 3 is a top plan view thereof.

I claim:

The ornamental design for an oil changer, as shown.

JOHN D. GRAY.
